UNITED STATES PATENT OFFICE.

WILLIAM E. TAYLOR, OF EASTPORT, MAINE, ASSIGNOR TO AMERICAN CAN COMPANY, OF NEW YORK, N. Y., A CORPORATION OF NEW JERSEY,

SHEET-METAL CAN FOR SARDINES.

1,112,037.

Specification of Letters Patent. Patented Sept. 29, 1914.

Application filed October 1, 1910. Serial No. 584,788.

To all whom it may concern:

Be it known that I, WILLIAM E. TAYLOR, a citizen of the United States, residing in Eastport, in the county of Washington and 5 State of Maine, have invented a new and useful Improvement in Sheet-Metal Cans for Sardines, of which the following is a specification.

My invention relates to improvements in 10 sheet metal cans for sardines or other articles.

The object of my invention is to provide a sheet metal sardine-can of a simple and efficient construction, capable of being cheaply manufactured, which may have its cover soldered on the body after the can is filled and without danger of scorching or injuring the contents of the can or the flavor thereof.

A further object is to provide my improved can with means for conveniently 20 opening the same.

My invention consists in the novel construction of parts and devices and in the novel combinations of parts and devices here- 25 in shown and described, and by which I ac- complish this object or result, the same being particularly set forth in the claims.

In the accompanying drawing forming a part of this specification, Figure 1 is a perspective view of a sheet metal can for sardines or other articles embodying my invention. Fig. 2 is a plan view. Fig. 3 is a section on line 3—3 of Fig. 2. Fig. 4 is a section across Fig. 1 and Fig. 5 is an enlarged detail vertical section through the soldered 35 seam. Fig. 6 is a similar view, showing a different shape of cover.

In the drawing, 1 represents the body of a sheet metal sardine can embodying my invention, the same being preferably a one 40 piece seamless drawn body. The can body 1 is provided at its upper end with an outstanding or right angle flange 2, the upper surface of which is preferably furnished with a solder film or coating 3, fusibly united 45 thereto at the can factory where the can is manufactured.

The cover 4 is preferably provided with an inwardly or downwardly projecting bead 5, the inner wall 6 of which is adapted to fit 50 snugly within the mouth of the can body and thus register the cover in position in respect to the body. The cover 4 is further provided with a laterally projecting seam flange 7, the outer portion 8 of which is

folded around and under the outstanding 55 flange 2 of the can body, thus forming it into an inturned flange which tightly embraces the outstanding flange of the can body and snugly clamps the cover on the can body with its seam flange 7 in close metal to 60 metal contact with the solder coated seam flange 2 of the can body.

To enable the can to be readily opened, the cover 4 is further preferably provided with a projecting lip or tongue 9, preferably at 65 one corner which is carried on the free and unsoldered folded portion 8 independent of the seam, so that it is not united to the under side of the seam element 2 by solder or by any interlocking bends, and is folded down 70 against the upright wall of the can body, as will be readily understood from Figs. 1 and 3 of the drawing. The cover 4 is further provided with a score or weakened line 10 extending from the edges of the tongue 9 75 diagonally across the seam flange 7 and along one end and one or both sides of the cover adjacent to the bead 5, as will be readily understood from Figs. 1, 2 and 5 of the drawing.

After the can has been filled with fish or other articles and the cover has been applied and its seam flange 7 folded at its outer portion 8 around the outstanding seam flange of the body, the cover is soldered to 85 the body preferably by application of heat to the outstanding seam flanges of the body and cover, thus fusing the solder film or coating between said seam flanges and thereby forming a hermetically tight soldered 90 seam or joint. As the seaming flanges of the body and cover are outwardly projecting, the soldering may be readily done without in any way injuring the contents of the can.

In practising my invention, I prefer to 95 provide the seam flange of the body with a coating of solder fusibly united thereto before the can is filled, as this renders it unnecessary to apply any molten solder to the seam flanges of the body and cover during 100 the solder or heat applying operation, and thus materially simplifies the closing of the cans by hermetically tight solder joints or seams.

In the modification illustrated in Fig. 6, 105 the cover 4 of the can is of a countersunk type and has an upright or countersunk wall 11 which fits inside the upper end or mouth

of the can body, this countersunk wall being employed instead of the inwardly projecting bead 5.

I claim:—

- 5 1. In a sardine can, the combination with a can body having an outstanding seam flange, of a cover having a longer outstanding seam flange soldered at its inner part to said seam flange of the body and provided 10 with an unsoldered inturned and free flange at its outer portion folded around and inclosing the soldered edge of said outstanding flange of the body, substantially as specified.
- 15 2. In a sardine can, the combination with a can body having an outstanding seam flange, of a cover having an outstanding seam flange soldered to said seam flange of the body and provided with an unsoldered inturned and free flange at its outer portion 20 folded around said outstanding flange of the body, said cover having a projecting tongue carried on the said free and unsoldered folded portion independent of the

seam, and scores or weakened lines extending from the edges thereof across the seam 25 flange and along the sides and end of the cover.

3. In a sardine can, the combination of a can body having an outstanding seam flange, and a cover having an outstanding seam 30 flange soldered to the seam flange of the body, one of the said flanges being longer than the other and extending beyond the soldering and the edge of the shorter flange, and being bent around the soldered edge of 35 the latter so as to be substantially parallel with the shorter flange, and to inclose the same, the said longer flange beyond the outer edge of the shorter flange being unconnected with and free from the shorter flange; sub- 40 stantially as set forth.

WILLIAM E. TAYLOR.
